UNITED STATES PATENT OFFICE.

CHARLES ADRIAN SAWYER, JR., OF NEWTON, MASSACHUSETTS.

LEATHER-WORKING MACHINE.

1,375,935.

Specification of Letters Patent. Patented Apr. 26, 1921.

Application filed May 8, 1920. Serial No. 379,731.

To all whom it may concern:

Be it known that I, CHARLES ADRIAN SAWYER, Jr., a citizen of the United States, and resident of Newton, in the county of 5 Middlesex and State of Massachusetts, have invented an Improvement in Leather-Working Machines, of which the following description, in connection with the accompanying drawings, is a specification, like 10 letters on the drawings representing like parts.

My present invention relates to leather working machines, and more particularly to leather working machines for blanking- 15 out shoe soles and the like.

In leather working machines of the dinker type in use at the present day, the side of leather is placed on the cutting block table of the machine, a steel cutting or clicking 20 die having a contour of the sole blank to be cut is placed in position on the side of leather and the beam or reciprocating member of the machine being released by means of a foot treadle, drops on the die, forcing 25 its contour knife edge through the leather.

A skilful operator is essential in order that good and efficient results may be obtained, and the waste of leather kept as low as possible. The chances of injury with the 30 usual dinker are so great that a careless operator is soon injured, while a careful operator consumes a great portion of his time in insuring his safety. I have found that the customary merchantable side of leather 35 suitable for the production of shoe sole blanks may be advantageously cut into strips or sections across the side from back to belly, the width of strip or section equaling the length of the particular size of sole

40 blank to be cut therefrom, and these strips or sections being somewhat less than the length and width of the bed of the usual type of dinker. Also I have found that shoe sole blanks, regardless of the length 45 thereof, have practically the same contour. I have therefore, designed a gang cutter which will replace the single clicking die formerly used and by cutting the side of leather into strips or sections, as above de-

50 scribed, I can so arrange my gang of cutters on the beam or reciprocating member of the machine as to insure the cutting of a plurality of sizes with absolutely no waste of leather in the length of the strip of 55 leather. With this method of operation, the

only waste is the trimming that is necessary along the narrow end of the strip of leather.

As the dinker is practically a press designed to impart a hammer blow to a clicking die, I prefer to refer to the dinker as a 60 press.

In my Patent No. 1,368,925, dated Feb. 8, 1921, I have described and claimed a dinker or press in which a plurality of parallelly arranged cutters are fixed in position on a 65 reciprocating head or holder for blanking-out a plurality of shoe sole blanks simultaneously. In my copending application, Serial No. 377,321, filed April 28, 1920, I have described and claimed a dinker or 70 press in which a plurality of cutters may be adjustably mounted on a reciprocating head or holder in position for blanking-out a plurality of shoe sole blanks simultaneously, the cutters being adjustable to permit the 75 blanking-out of shoe sole blanks of various sizes with but one set of cutters. In the present application, I have described and claimed a dinker or press, which may be accurately denominated a skip dinker, in 80 which but one pair of parallelly arranged cutters is employed, and so operate the mechanism of the press as to blank out every alternate shoe sole blank that may be cut from a strip or sheet of sole leather, the cutters being adjustable on the reciprocating 85 head or holder, if desired.

An object of my invention therefore, is a dinker or press in which a pair of substantially parallelly arranged cutters may 90 be used to blank-out alternate shoe sole blanks from a strip of sole leather.

In the ordinary dinker, a base block of wood is employed on which to rest the strip or sheet of sole leather, and as the die used 95 is a complete outline of the shoe sole blank desired, and is manually placed in position on the strip of leather, it is possible to obtain fairly even wear over the entire surface of the base block. With a press, such as 100 those described in my copending applications above referred to, wherein a plurality of parallelly arranged cutters are employed, the wear is confined to practically a plurality of parallel lines, with the result that the 105 base block is soon rendered unfit for service. With a view to remedying this defect, I have designed a base block and holder therefor, in which the base block may be moved laterally with respect to the plurality of 110

parallelly arranged cutters, with the result that the wear is evenly distributed over the entire surface of such base block.

Another object of my invention therefore, 5 is an improved base block and holder for insuring an even wear of the surface thereof.

Other objects and novel features of construction and arrangement of parts will appear as the description of the invention progresses.

In the accompanying drawings,

Figure 1 is a front elevation,

Fig. 2 is a side elevation of the right hand side of the machine,

15 Fig. 3 is a vertical section on the line 3—3 of Fig. 1,

Fig. 4 is a vertical section on the line 4—4 of Fig. 1.

20 Fig. 5 is a fragmentary plan view, showing the details of construction of the cutter head operating mechanism,

Fig. 6 is a fragmentary side elevation of Fig. 5,

25 Fig. 7 is a front elevation of a modification of the base block used in connection with my improved machine,

Fig. 8 is a plan view of Fig. 7, and

30 Fig. 9 is a detail showing the construction of the means for controlling the engagement of the pawls with the sliding and fixed bars.

Referring to the drawings, 10 designates side members or standards tied together at the bottom by a rod 11 and having bosses 35 12 and 13, the faces of which lie in the same inclined plane.

40 Mounted on the bosses 12 and 13 in inclined position is a frame member 14 near the top of which are alined bearings 15 in which is rotatably mounted the main shaft 16. On one end of the shaft 16 is rotatably mounted the fly wheel 17, a nut 18 being provided to hold the fly wheel 17 on the shaft. The lower end of the member 14 is 45 provided with a cross bar 19, through which are threaded a plurality of adjusting bolts 20 engaging the lower face of the slideable table 21. This table 21 is provided with ledges 22 and 23 on its front and rear sides 50 respectively, to aid a base block 24, a gib 25 and set screws 26 coöperating with the ledge 22 for holding the base block 24 rigidly in position.

55 Slidably mounted in the member 14 and above the block above described, is a cutter head 32, provided with a shaft 33 arranged parallel to the main shaft 16. Attached to the shaft 33, near each end thereof, are the lower ends of connecting rods 60 34, the upper ends of which are provided with bearings 35 engaging with eccentrics 36 keyed to the main shaft 16. Rotation of the main shaft 16 will cause a reciprocating movement of the head 32 toward and 65 from the block elements 31.

Mounted on the lower portion of the head 32 and for sliding movement thereon, is a holder 37, to the lower face of which is attached, in any convenient manner, a pair of cutting knives 38, defining the contour of 70 a shoe sole blank of any desired size.

Fixed to the main shaft 16, between the bearing 15 and the hub 47 of the fly wheel 17, is a collar 44 provided with a channel 45, as shown. Slidably mounted in the collar 44 and parallel to the shaft 16 is a pin 46, which, in its forward movement, or movement to the right, as shown in Fig. 1, engages in a hole in the hub 47 of the fly wheel 17. This pin 46 has a projection at 80 one side thereof which is guided in a slot 48 in one of the walls defining the channel 45. The projection on the pin 46 is beveled, and is adapted to be engaged by a bevel on the upper end of the rod 55, pivotally mounted at 56 on the frame member 14, this rod lying normally in the channel 45 and retained there under normal conditions by the spring 57, a plate 58 on the frame member 14 holding the rod 55 in alinement with 90 the channel.

95 Pivotally mounted on either side of the frame member 14 are bell crank levers, each having an arm 59 extending outwardly to a position in front of the frame member and to the outer end is pivotally mounted the lower edge of the operating guard plate 60 slidably mounted in a substantially vertical plane in guideways 61 attached to either side of the front of the frame member. 100 The other arm 62 of the bell crank levers extends substantially parallel to the rod 55 and is provided with a projection or latch 63 adapted to engage with an edge of said rod 55 to rotate said rod on its pivot against 105 the tension of the spring 57 and force its upper beveled end out of the channel 45, this action allowing the pin 46 to be forced into the hole in the hub 47 to lock the main shaft 16 and fly wheel 17 together. For convenience in manufacturing, and to prevent unnecessary duplication of parts, the bell crank lever at the left of frame 14 is provided with an arm 62, but, as there is only one rod 55, the arm 62 only on the right of the frame member 14 performs any function. Pivotally mounted at the same point as each of the bell crank levers, above referred to, is a lever, one arm 69 of which is provided with a boss 70, adapted to engage with the 110 arm 59 of the bell crank lever. The other arm 71 of the lever extends rearwardly and has pivotally mounted at its end, the lower end of a connecting rod 72, a shaft 73 extending across the back of the frame member 14 and being rigidly attached to the upper ends of the connecting rods 72. Stops 74, adjustably mounted on the shaft 73, act 115 as stops or gages for the stock placed on the block elements 31.

Mounted in the frame member 14, at one side thereof and parallel to the main shaft 16, is a fixed bar 75, provided on its top edge with a plurality of spaced notches 76. 5 A second bar 77, arranged parallel to the bar 75 but spaced apart therefrom, as shown in Fig. 4, is provided on its upper edge with a plurality of ratchet teeth 78, this bar 77 being mounted in the frame member 14 for 10 sliding movement. One end of this bar 78 extends outward beyond the frame member 14 and is pivotally mounted to one end of an operating lever 79, the other end of this lever 79 being pivotally mounted on the 15 bracket 80, secured to the frame member 14, as shown in Figs. 5 and 6. Intermediate the ends of the lever 79 is a bolt 81 on which is mounted a roller 82 engaging in a cam groove 83 in a cam 84 secured to an extension 20 of the main shaft 16.

Mounted in the frame member 14, parallel to and beneath the bars 75 and 77, is a shaft 85, on which is slidably mounted a carrier member 86, a bar 87 rigidly connecting the member 86 with the head 37. Pivotally mounted in the member 86 on the pin 88 are two pawls 89 and 90, the pawl 89 engaging with the spaced ratchet teeth 78 in the sliding bar 77, while the pawl 90 engages with the spaced notches 76 in the fixed bar 75. The pawls are located side by side, and are each equal in width to the thickness of either of the bars 75 or 77, plus one-half the width of the space between said bars, and are held 35 in operative relation with said bars by springs 91, attached one end to an extension on the pawls and the other end to the carrier member 86 but one of said springs 91, that in Fig. 1, being shown.

40 Fixed to the frame member 14, and parallel to the main shaft 16, is a shaft 92 on which is rotatably mounted a sleeve 93, a collar 94, fixed to the shaft 92, limiting the movement of the sleeve 93. A spring 95, on 45 the shaft 92, and between the end of the sleeve 93 remote from the collar 94, and a hub 96 on the frame member 14, holds the sleeve 93 yieldingly against the collar 94. There is a hub 96 located on the shaft 92 50 against the inner sides of the frame members 14, and formed integral with these hubs and extending inwardly toward the center of the machine, as viewed in Fig. 3, is an arm 97, the outer end of this arm being positioned 55 above the parallelly arranged bars 75 and 77, in position to engage with a straight edge 98, located between said bars 75 and 77 and movable laterally with respect thereto to engage with the pawls 89 and 90 to free the 60 same from engagement with the ratchet teeth 78 and notches 76. A downward extension 99 on the sleeve 93, is in alinement with a slidable bar 100 in the frame member 14 and with the fixed bar 101 in the carrier member 86, the function and operation of

which will be hereinafter described. Also formed integral with the sleeve 93 and extending inwardly toward the center of the machine, is an arm 102, provided at its end with the roller 103 adapted to be moved into 70 engagement with a cam 104 fixed to the main shaft 16. The shaft 92 extends through the frame member 14 and at the ends thereof outside the frame member 14 are attached depending arms 105, a spring 106, for each 75 arm 105, being attached one end to the arm and the other end to the frame member 14. These springs 106 rotate the shaft 92 in an anti-clockwise direction under normal conditions, and hold the end of the arm 97 out 80 of engagement with the straight edge 98. At the lower end of each arm 105 is a swivelled lug 107, through which passes the threaded end of a rod 108, nuts 109 located on the rod 108 and on each side of the lug 85 107 providing means for adjusting the operative length of said rod 108. The other end of the rods 108 are pivotally attached to latch bars 109, intermediate the ends thereof. These latch bars 109 are pivotally attached 90 at their lower ends to stub shafts 110 extending outwardly from the stripper bar frame 111, while the upper ends are hook shaped at 112, to engage with outwardly extending teeth 113 on the reciprocating head 32. Also 95 attached at each side of the stripper bar frame 111 are studs 114 to which are attached one end of the springs 115, the other ends of which are attached to tension bars 116 at each side of the machine, adjusting 100 bolts 117 passing through plates 118 and threaded into the tension bars 116, providing suitable tensioning means.

The carrier means 86 is drilled to receive a rod 119, a pin 120 passing through a perforation in the carrier means 86 and rod 119 to lock said rod 119 in position. This rod 119 is advanced step by step to the right, as viewed in Fig. 1, until it comes into engagement with a depending arm 121, formed integral with the sleeve 93, when further movement forces the sleeve to the right, against the tension of spring 95, into engagement with the rod 122, slidably mounted in the frame member 14. This rod 122 engages 110 with the free end of the flat spring plate 123, the other end being riveted or otherwise secured to the pivoted rod 55. Adjacent and parallel to the rod 122 and securely fastened in the frame member 14, is a stud 124, 115 which co-operates with the stud 125 riveted near the free end of the spring plate 123, these two studs 124 and 125 acting as a locking means to hold the pivoted rod 55 out of the channel 45 when it is desired to operate 125 the machine.

The pitch or throw of the cam groove 83 is such as to cause a reciprocating movement of the sliding bar 77 equal to the width of two shoe sole blanks; that is, the pair of 130

cutters 38 on the slidable head 37 will be moved to the right, as viewed in Fig. 1, from the position shown to the correct position to blank out the third shoe sole blank 5 on the strip or sheet of leather. As the right hand cutter 38 simultaneously defines the right hand longitudinal edge of shoe sole blank No. 1, and the left hand longitudinal edge of shoe sole blank No. 2, blank No. 2 10 being in reverse position with respect to blank No. 1, the left hand cutter 38 in its second position will define the right hand longitudinal edge of sole blank No. 2, while both cutters 38, in the second position, will 15 define shoe sole blank No. 3. By this means and method of operation, I am enabled to practically double the cutting capacity of a single pair of cutters, as shown.

Referring now to Figs. 7 and 8 wherein 20 I have illustrated a modification of the base block 24 used in my improved machine, 124^a designates a frame provided at each end with a plurality of threaded bosses 27 to receive the screws 28. These screws 28 are 25 provided at one end with hand wheels 29, the other end engages with compression plates 30. Between the plates 30 are located a plurality of wood blocks 31 which rest on the top of the slidable table 21. By 30 compressing the blocks 31 between the compression plates 30 by means of the screws 28, I provide a practically solid block, the elements of which are readily renewable. Further, by backing off the screws 28 at 35 one end of the frame, and advancing the screws 28 at the other end, I am enabled to move the entire block laterally of the cutters insuring an even wear over the entire upper surface of the block elements 31.

40 The operation of my improved machine is as follows, it being assumed that all parts are in normal position, with the fly wheel rotating and with the free end of the rod 55 in the channel 45 to hold the pin 46 out 45 of engagement with the hub of the fly wheel; with the operating guard plate 60 downward to expose the opening between the pair of cutters and the top of the base block; with the gage or stop 74 above and at 50 the rear of the said block, and with the pair of cutters 38 at the left of the machine, as viewed in Fig. 1. The operator inserts a strip or sheet of sole leather on the block 31, the gages 74 insuring that such sheet of leather is in proper position on the base block. In order to properly operate the machine, both hands must be employed, and the operator therefore lifts the plate 60 in its guides 61 raising the same to block 55 access to the knives and rotating the bell crank lever on its axis, forcing the latch 63 on the arm 62 against the rod 55, thus forcing the beveled end of the rod 55 out of the channel 45, whereupon the pin 46 will be 60 forced into the hole in the hub 47 of the fly

wheel 17, locking said fly wheel and main shaft 16 together. The main shaft 16 thereupon rotates, and through the eccentric 36 causes a reciprocating movement of the head 32 and therefore the cutters 38. The 70 holder 37 is held in the position shown in Fig. 1 by means of the weight 120 attached to the metallic tape 126 passing over a pulley 127 on the end of the shaft 65. The other end of the tape is fastened to the 75 holder 86. The cam groove in the cam 84 is so shaped as to maintain the sliding bar 77 stationary, and therefore, while the pawl 89 engages with one of the teeth 78 in the sliding bar, there is no longitudinal motion 80 along the head 32 transmitted to the holder 37. Simultaneously with the operation of the rod 55, the stud 125 on the spring plate 123 is sprung over the stud 124 in the frame member 14, so as to occupy the position in 85 front or to the left of said stud 124, as viewed in Fig. 2, the rod 55 being thus held out of the channel 45 against the tension of the spring 103.

90 On the upward movement of the reciprocating head 32, the cam groove 83 forces the slidable bar 77 to the right, as viewed in Fig. 1, and the pawl 89, being in engagement with one of the notches 76 in said bar, the head 32, holder 37 and cutters 38 are 95 moved to the right a distance equal to the width of two shoe sole blanks. On the continued rotation of the main shaft 16, the cam groove 83 forces the sliding bar 77 to the left, but the movement of said bar 77 100 to the right was sufficient to allow the pawl 90 to engage in one of the notches 76 on the bottom edge of the fixed bar 75, so that the head 32, holder 37 and cutters 38 remain in 105 their new position during the return of the bar 77 to normal. The sequence of operations above described is repeated until the pin 119 engages with and forces the arm 121, and therefore, the sleeve 93, to the right 110 into position to bring the roller 103 on the arm 102 in line with the cam 104 on the shaft 16, and also moves the pin 122 to the right against the free end of the spring plate 123, freeing the stud 125 on the plate 123 from 115 the stud 124 on the frame member 14, whereupon the spring 106 moves the upper end of the rod 55 into the channel 45, stopping the rotation of the main shaft 16. Depression of the free end of the arm 102 by the cam 104 causes a rotation of the shaft 92. Rotation of the shaft 92 moves the free 120 end of arms 105 outwardly and the rod 108 pulls the latch bar 109 to the right, as viewed in Fig. 2, to engage the hook 112 to engage 125 with the teeth 113 on the reciprocating head 32, so that during the last upward stroke of the head 32, the stripper bar frame will be brought up also. The rotation of the shaft 92 also causes a depression of the free ends of the arms 97, which engage with and 130

depress the straight edge 98 sufficiently to free the pawls 89 and 90 from the bars 77 and 75 respectively, whereupon the holder 37 and parts associated therewith are returned to normal position, by the weight 120.

It will be evident from the above description, that my improved skip-dinker is capable of blanking out shoe soles from leather or other material, by the use of a single 10 pair of cutters, the number of sole blanks cut being equal to twice the number of strokes of the cutters, minus one. Further, that, in contradistinction to the dinkers described and claimed in my copending applications above referred to, where the main 15 shaft is rotated once for each movement of the clutch rod, I provide means for causing a continuous rotation of the main shaft during the intermittent feed of the cutters from one side of the machine to the other, when the main shaft is automatically stopped. Again the machine may be made of any length desired, the automatic stopping mechanism not operating until after the last 20 stroke of the cutters, and by using rods 119 of different lengths, this last stroke of the cutters may take place at any point along the length of the machine desired.

My invention is further described and defined in the form of claims as follows:

1. In a leather working machine, the combination of a frame, a pair of cutters mounted for reciprocating and sliding movement therein, a rotatable shaft, means operated 35 thereby for causing a reciprocating and sliding movement of the pair of cutters, a source of power and a combined operating and guard plate slidable with respect to said

frame and operating to connect said shaft with the source of power, whereby an intermittent reciprocating and sliding movement is imparted to said cutters and the operator is simultaneously guarded from injury by the cutters.

2. In a leather working machine, the combination of a frame, a source of power, a rotatable shaft in said frame, a clutch for connecting said shaft to said source of power, a cutter head mounted for reciprocation in said frame, a cutter holder, means 45 for moving said cutter holder step by step in said frame, means for locking the cutter holder in position after each movement, means for returning said cutter holder to normal position and for simultaneously disconnecting the shaft from the source of power.

3. In a leather working machine, the combination of a shaft, a frame, a cutter holder 50 slidable on said frame, a fixed notched bar in said frame, a slidably notched bar in said frame, pawls on said cutter holder engaging with said bars respectively, means for reciprocating said slidable notched bar to cause a step by step movement of said cutter holder on said frame, said cutter head being held in position at the end of each step by step movement by the pawl engaging in the notches of the fixed bar, and means for moving said pawls out of engagement with the bars to allow the cutter holder to return to normal position.

In testimony whereof, I have signed my name to this specification.

CHARLES ADRIAN SAWYER, JR.
